CLAIM

The ornamental design for a carabiner, as shown and described.

DESCRIPTION

FIG. 1 is a perspective view of a carabiner, showing my new design;

FIG. 2 is a front elevational view of the invention;

FIG. 3 is a rear elevational view of the invention;

FIG. 4 is a left-side elevational view of the invention;

FIG. 5 is a right-side elevational view of the invention;

FIG. 6 is a top plan view of the invention;

FIG. 7 is a bottom plan view of the invention;

FIG. 8 is a perspective view of the carabiner shown in FIG. 1, in its environment of use;

FIG. 9 is a perspective view of an additional embodiment of a carabiner, showing my new design;

FIG. 10 is a front elevational view of the embodiment shown in FIG. 9;

FIG. 11 is a rear elevational view of the embodiment shown in FIG. 9;

FIG. 12 is a left-side elevational view of the embodiment shown in FIG. 9;

FIG. 13 is a right-side elevational view of the embodiment shown in FIG. 9;

FIG. 14 is a top plan view of the embodiment shown in FIG. 9;

FIG. 15 is a bottom plan view of the embodiment shown in FIG. 9; and,

FIG. 16 is a perspective view of the additional embodiment of the carabiner shown in FIG. 9, in its environment of use.

The broken lines in FIGS. 8 and 16 are included for the purpose of illustrating the item in its environment of use and form no part of the claimed design.
